SELDEN N. RISLEY, OF BROOKLYN, NEW YORK.

Letters Patent No. 84,906, dated December 15, 1868.

—
CIGAR-CASE.
—

The Schedule referred to in these Letters Patent and making part of the same.

To all whom it may concern:

Be it known that I, SELDEN N. RISLEY, of Brooklyn, in the county of Kings, and State of New York, have invented a certain new and useful Improvement in Cigar-Cases; and I do hereby declare that the following is a full, clear, and exact description of the same, reference being had to the accompanying drawing, making a part of this specification, and to the letters of reference marked thereon.

The necessity for protecting cigars, when being carried about the person, has led to the manufacture of a variety of cases, that are usually more costly than the cigars they are employed to protect.

The object of my invention is to provide an efficient pocket-case, for the convenient and safe carriage of cigars, that will be neat in appearance, and may be made with appropriate inscriptions, and so cheaply that it will serve as an inexpensive advertising-medium, which may be furnished by dealers for but a small charge, or with no charge at all, to the retail purchasers of a few cigars, instead of the ordinary paper bags or wrappers.

To accomplish this object, the said invention consists of one or more tubes, that are made of paper, suitably struck up, or embossed, or moulded in separate halves, which are subsequently glued together to form separate compartments, of about the size and form of ordinary cigars, the points of junction forming ribs that stiffen the article longitudinally and at the bottom, the top being stiffened, and the article completed by gluing an additional strip there to strengthen the openings of the tubes.

The blanks may be printed, before they are embossed, with any inscription that may be desired by the dealer, to serve as an advertisement or business-card.

To enable others skilled in the art to which it ap-

pertains to make and use my invention, I will proceed to describe its construction and operation with reference to the drawing.

Figure 1 represents the completed article, and

Figure 2, the paper as it is struck up by the dies.

The blanks are first moulded, of good manilla or other paper, of similar quality, between male and female dies, by which they are shaped to the form shown in fig. 2. Glue or paste is then applied around the edges *a*, and on the dividing ridges or partitions *b*, and the halves are then folded together between moulds, and the compartments definitely shaped by the insertion of a cylindrical mandrel into each of the openings, the points of the mandrels being of a spindle-form to shape the bottom of each tube or receptacle like the point of a cigar.

The article is completed by fastening an additional ring, *c*, around the open end of the case, to restrain the tendency to spread at that point, and the consequent collapse of the openings, by which it is most likely to get out of shape.

This ring may be struck or stamped out of very thin sheet-metal, to furnish a superior or more fancy finish.

The circular sections and longitudinal ribs, and the retaining-ring at the open end, give the article thus made a degree of strength and stiffness amply sufficient for the purpose intended, although made merely of ordinary wrapping-paper.

I claim, as a new article of manufacture—

A cigar-case, made of paper tubes, with longitudinal ribs and a retaining-ring, substantially as described.

S. N. RISLEY.
